UNITED STATES PATENT OFFICE

WALTER KIRSNER, OF NEW YORK, N. Y., ASSIGNOR TO GRAYSON SHOPS, INC., A CORPORATION OF NEW YORK

DESIGN FOR A STORE FRONT

Application filed July 13, 1929. Serial No. 32,037. Term of patent 14 years.

To all whom it may concern:

Be it known that I, WALTER KIRSNER, a citizen of the United States, and resident of New York city, New York, have invented a certain new, original, and ornamental Design for Store Front, of which the following is a specification, reference being had to the accompanying drawing, forming part thereof.

Fig. 1 is a front view of a store front showing my new design.

Fig. 2 is a section view taken on the line 2—2 of Fig. 1.

I claim:

The ornamental design for a store front as shown.

WALTER KIRSNER.
